(57) **CLAIM**

The ornamental design for filtering system for fluid, as shown and described.

DESCRIPTION

FIG. 1 is a front elevational view of filtering system for fluid showing our new design;

FIG. 2 is a side elevational view thereof;

FIG. 3 is a top plan view thereof;

FIG. 4 is a bottom plan view thereof; and,

FIG. 5 is a perspective view thereof.

1 Claim, 5 Drawing Sheets

FIG. 1

FIG. 2

FIG. 3

FIG. 4

FIG. 5
